UNITED STATES PATENT OFFICE.

LEON J. RAINAUD, OF MERIDEN, CONNECTICUT.

DESIGN FOR A SHADE-HOLDER.

36,474.

Specification for Design. Patented Oct. 26, 1920.

Application filed March 12, 1920. Serial No. 365,325. Term of patent 3½ years.

To all whom it may concern:

Be it known that I, LEON J. RAINAUD, a citizen of the United States, and a resident of Meriden, in the county of New Haven, State of Connecticut, have invented a new, original, and ornamental Design for a Shade-Holder, of which the following is a specification, reference being had to the accompanying drawing, forming part hereof.

In the drawing—

The figure is a perspective view of a shade holder showing my new design.

I claim:—

The ornamental design for a shade holder as shown.

LEON J. RAINAUD.
